US0D1051091S

(12) **United States Design Patent** (10) Patent No.: **US D1,051,091 S**
(45) Date of Patent: ** Nov. 12, 2024

(54) **EARPIECE**

(71) Applicant: **SHENZHEN SHOKZ CO., LTD.**,
Guangdong (CN)

(72) Inventors: **Haofeng Zhang**, Shenzhen (CN);
Yongjian Li, Shenzhen (CN); **Lei Zhang**, Shenzhen (CN); **Lei Tang**, Shenzhen (CN); **Zeying Zheng**, Shenzhen (CN); **Yunbin Chen**, Shenzhen (CN)

(73) Assignee: **SHENZHEN SHOKZ CO., LTD.**,
Shenzhen (CN)

(**) Term: **15 Years**

(21) Appl. No.: **29/878,368**

(22) Filed: **Jun. 20, 2023**

Related U.S. Application Data

(60) Division of application No. 29/784,599, filed on May 20, 2021, now Pat. No. Des. 995,468, which is a continuation of application No. 29/781,986, filed on May 3, 2021, now Pat. No. Des. 996,391.

(30) **Foreign Application Priority Data**

Nov. 20, 2020 (CN) 202030709008.1

(51) LOC (14) Cl. **14-01**

(52) U.S. Cl.

USPC **D14/205**

(58) **Field of Classification Search**

USPC D14/205; D24/174; 128/864-866;
381/380-381

CPC H04R 1/10; H04R 1/1066; H04R 1/1033;
H04R 1/1075; F21V 33/0056

See application file for complete search history.

(57) **CLAIM**

The ornamental design for an earpiece as shown and described.

DESCRIPTION

FIG. 1 is a perspective view of the back, bottom, and right side view showing the new design;
FIG. 2 is a perspective view of the back, top, and left side view thereof;

FIG. 3 is a top view thereof;

FIG. 4 is a bottom view thereof;

FIG. 5 is a right side elevation view thereof;

FIG. 6 is a left side elevation view thereof;

FIG. 7 is a rear elevation view thereof; and,

FIG. 8 is a front elevation view thereof.

The short dash broken lines indicate portions of the bone conduction headphone that form no part of the claimed design.

1 Claim, 7 Drawing Sheets
